UNITED STATES PATENT OFFICE.

RICHARD M. PANCOAST, OF CAMDEN, NEW JERSEY.

DESIGN FOR A VENTILATOR.

SPECIFICATION forming part of Design No. 33,429, dated October 23, 1900.

Application filed September 26, 1900. Serial No. 31,215. Term of patent 14 years.

To all whom it may concern:

Be it known that I, RICHARD M. PANCOAST, a citizen of the United States, residing at Camden, in the county of Camden and State of New Jersey, have invented and produced a new and original Design for a Ventilator; and I do declare the following to be a full, clear, and exact description of the same, reference being had to the accompanying drawings, forming a part thereof.

Figure 1 is a perspective view of a ventilator, showing my new design. Fig. 2 is a horizontal sectional plan view showing the lower half of Fig. 1.

As shown by the figures of the drawings, the leading or characteristic features of my design consist in the horizontal flanges and upwardly-projecting curved ribs of the bottom portion at the ends, the downwardly-projecting curved ribs of the upper portion at the ends, the bent sides, and the ends having curved surfaces, there being a central opening through the bottom portion and two openings at each side between adjacent edges of the irregular-shaped sides and the ends having curved surfaces.

Referring to the figures, the letter A designates the top of the ventilator, which is bounded by an irregular line, but symmetrically curved at the ends; B, downwardly-projecting curved flanges or ribs; C, downwardly-projecting lugs; D, horizontal projecting flanges of the bottom portion; E, the curved ends of the bottom portion; F, upwardly-projecting curved ribs of the bottom portion; G, a central opening through the bottom portion; H, upwardly-projecting ribs coinciding in part with the boundary-line of the opening through the bottom; I, upwardly-

projecting lugs from the top surface of the bottom portion; J, the irregular-shaped sides of the ventilator, having flared edges; K, the ends, having exterior curved or convex surfaces and interior concave surfaces, and M represents perpendicular rods extending from the top to the bottom of the ventilator and located adjacent the sides and ends and symmetrically arranged relative to the opening through the bottom.

Openings L exist between the perpendicular flared edges of the sides and the perpendicular edges of the concavo-convex-shaped end portions.

As a whole the ventilator appears to the eye as a statical structure having a bottom portion, with projecting flanges and upwardly-projecting ribs at the ends, a top portion, of irregular outline, curved at the ends, and with downwardly-projecting curved ribs also at the ends, sides of irregular shape, ends of curved surfaces matching the curves of the upwardly and downwardly projecting ribs and having openings at the sides, bounded by the perpendicular edges of the curved end portions and the perpendicular edges of the flared ends of the irregular-shaped side portions.

Having described my invention, what I claim as new, and desire to secure by Letters Patent, is—

The design for a ventilator, as herein shown and described.

In testimony whereof I affix my signature in presence of two witnesses.

RICHARD M. PANCOAST.
